UNITED STATES PATENT OFFICE

GEORGE SPERTI, OF COVINGTON, KENTUCKY, ASSIGNOR TO SPERTI LAMP CORPORATION, OF NEW YORK, N. Y., A CORPORATION OF DELAWARE

LAMP

Application filed April 30, 1931. Serial No. 534,022.

This invention relates to ultra-violet lamps and particularly to lamps of this character which embody an arc such as a mercury arc.

Recent investigations in connection with the properties and action of ultra-violet radiation have led to an extended application of ultra-violet rays for therapeutic and other purposes. For example, ultra-violet lamps are extensively used for the irradiation of living subjects, both in clinics and in the home. The use of ultra-violet lamps for activating vitamins in food products is also well-known, and the action of ultra-violet rays in sterilizing liquids and foods, in stopping enzyme action, etc., has been greatly developed. This wide use of ultra-violet radiation has resulted in the designing and building of various kinds of ultra-violet lamps, of which the most practicable at present is the mercury arc.

The object of the present invention is to provide a novel mercury arc lamp which is simple, cheap and durable in construction, economical and efficient in operation, and easy to start and operate without special equipment and without manual manipulation of the lamp such as tipping, etc.

One embodiment of the invention is illustrated in the accompanying drawing, but it is to be expressly understood that said drawing is for purposes of illustration only and is not to be construed as a definition of the limits of the invention, reference being had to the appended claims for this purpose.

In the drawing,

Fig. 1 is a diagrammatic perspective view of a lamp embodying the invention; and

Fig. 2 is a sectional view of the lamp shown in Fig. 1.

In the form shown, the lamp is designed for operation on alternating current. The lamp casing or chamber 1, which may be of any suitable material translucent to ultra-violet radiation, comprises in the form shown a substantially U-shaped tube having pools of mercury 2 and 3 in the legs of the U which constitute mercury electrodes. Obviously the lamp chamber 1 may have any other suitable shape. The lamp chamber may be of quartz glass, which transmits substantially the com-

plete spectrum of the mercury arc, or it may be of special filtering glass or combined with a suitable filter so that the lamp does not emit waves shorter than a desired short wave length limit. Such filtering characteristics are desirable in many instances where certain waves cause harmful or destructive effects.

The electrodes 2 and 3 are connected to a suitable source of alternating current by means of wires 4 and 5. In the form shown, the lamp is operated from a transformer comprising primary and secondary windings 6 and 7, the terminals of the secondary winding being connected to wires 4 and 5. The secondary winding may likewise be shunted by a condenser 8.

In the usual mercury arc lamp, the arc is started either by tipping the lamp or by applying heat to one of the mercury pools so as to vaporize a portion of the mercury. The present invention embodies an arc starting means which is enclosed in the lamp chamber 1 intermediate the electrodes 2 and 3 and which preferably comprises a member of ion adsorbing material such as zirconium oxide, thorium oxide, etc., which on being heated gives off its adsorbed mercury ions and causes the arc to strike between electrodes 2 and 3. In the form shown, the arc starting means comprises a tube 9, preferably of zirconium oxide, placed in the lamp chamber substantially midway between the electrodes 2 and 3. Within the tube 9 is a heating coil 10 the terminals of which may be connected to any suitable external source of current by means of wires 11 and 12.

When the lamp is to be used, current is supplied to the primary transformer winding 6 and the induced voltage in the secondary winding 7, is applied to electrodes 2 and 3. At the same time the heating coil 10 is energized so that the tube 9 is heated. Mercury ions are thus driven off from the tube 9 and fill the lamp chamber 1 sufficiently to cause the arc to jump between the electrodes 2 and 3.

This lamp comprises but a single integral unit, is of very simple design and construction and embodies no parts which can get out of order or require adjustment. The use of

the arc starting means renders it unnecessary to provide special starting equipment such as mechanical arrangements for tilting or tipping the lamp or external heating means to vaporize the mercury from pools 2 and 3. The lamp is always ready for use and it is only necessary to turn a switch in order to start the operation.

It will be understood that the invention is not limited to the particular embodiment illustrated and described and that changes may be made in the details of construction and arrangements of the parts without departing from the spirit of the invention. Reference is therefore to be had to the appended claims for a definition of the limits of the invention.

What is claimed is:

1. An alternating current ultra-violet lamp comprising in combination a casing translucent to ultra-violet light, spaced mercury pools in said casing, means for connecting said pools to a source of potential, and an arc starting means in said casing intermediate said pools comprising a refractory oxide member and means for heating said member to drive off mercury ions.

2. An alternating current ultra-violet lamp comprising in combination a lamp chamber of material translucent to ultra-violet light of the desired wave lengths, spaced mercury electrodes in said chamber, means for connecting said electrodes to an external source of potential, a refractory oxide member in said chamber intermediate said electrodes, and electric resistance means adjacent said member and connected to an external source of current for heating said member to drive off mercury ions therefrom.

3. An alternating current ultra-violet lamp comprising in combination a chamber translucent to ultra-violet light, spaced mercury electrodes in said casing, means for connecting said electrodes to an external source of potential, a tube of ion adsorbing material in said chamber intermediate said electrodes, a resistance coil in said tube for heating the same, and means for connecting said resistance coil to an external source of current.

4. An ultra-violet lamp comprising in combination a casing translucent to ultra-violet light of the desired wave lengths, spaced mercury electrodes in said casing, means for connecting said electrodes to an external source of potential, and an arc starting means in said casing intermediate said electrodes and comprising a tube of zirconium oxide, a resistance coil in said tube, and means for connecting said resistance coil to an external source of current.

5. An alternating current ultra-violet lamp comprising in combination a lamp chamber translucent to ultra-violet radiation of the desired wave lengths, said chamber being substantially U-shaped, spaced mercury pools in the legs of the U and constituting mer-

cury electrodes, means for connecting said mercury electrodes to an external source of potential, a refractory oxide member positioned in said chamber substantially midway between the legs of the U, a resistance coil adjacent said member, and means for connecting said resistance coil to an external source of current.

In testimony whereof I have signed this specification.

GEORGE SPERTI.
